Primary Examiner — Mehri F Bajoul(74) *Attorney, Agent, or Firm* — Thomas A. O'Rourke; Bodner & O'Rourke, LLP(57) **CLAIM**

The ornamental design for a ball launching device, as shown and described.

DESCRIPTION

FIG. 1 is a perspective view illustrating a new ornamental design for a ball launching device;

FIG. 2 is a side elevation view thereof;

FIG. 3 is a top plan view thereof;

FIG. 4 is a bottom plan view thereof;

FIG. 5 is a rear elevation view thereof; and,

FIG. 6 is a front elevation view thereof.
